Fig. 6

Figures 4 and 5 are sections on the respective lines 4—4; 5—5 of Figure 1; and

The essential features of my design for a spoon or similar article reside in the configuration of the handle in combination with the particular type of ornamentation as applied thereto.

I claim:

The ornamental design for a spoon or similar article, substantially as shown and described.
